Application April 14, 1953, Serial No. 348,674

8 Claims. (Cl. 240—9)

This invention relates to luminaires generally, and more particularly to elongated luminaires which are adapted for a variety of purposes and arrangements.

The invention as herein illustrated embodies forms of luminaires which are adapted to be mounted in ceiling recesses; however, certain features thereof are equally useful in luminaires recessed in openings other than in ceilings, and other features are equally useful in luminaires which are not mounted in recesses.

One problem encountered in recessing luminaires resides in the variety of openings or ceiling constructions in common use, therefore one important object of this invention is to provide a standard form of luminaire which is readily adaptable to a variety of building constructions.

While certain details of luminaires used in different types of building constructions necessarily vary in certain features thereof, another important object of this invention is to provide for standard component parts which are particularly constructed to be cooperable with a number of different types of luminaires.

Luminaires of the type described herein generally have substantially inverted U-shaped housings with a shielding device for the open side, which may be either a framed louver assembly or a framed translucent cover assembly. Such housings may be mounted individually with end plates closing the ends of the housing or in continuous rows of housings mounted in tandem in either parallel or intersecting lines. In the past such arrangements have had objectionable light leakage at the edges of the shielding devices, particularly when the housings are aligned so that a continuous line of shielding devices are arranged in an end-to-end relationship. Another important object of this invention is, therefore, to provide a luminaire construction having novel provision for preventing leakage of light around the edges of the shielding devices, irrespective of the number employed or the arrangement thereof.

It is also an object of this invention to provide a novel form of recessed luminaire housing in the form of a trough having novel means for mounting other components therein, so that all installation work may be done from the open side of the trough.

Another object of this invention is to provide a recessed luminaire housing of trough shape having a novel end construction which may be cooperable with either covering plates or coupling elements so that the end plates and coupling elements may be readily installed from the open side of the housing, either before or after the ceiling installation.

Still another object of this invention is to provide a recessed type of luminaire having an inverted U-shaped housing with novel means for securing the housing to a variety of standard support members from the open side of the housing.

Yet another object of this invention is to provide a recessed type of luminaire having a trough shaped housing with a novel intermediate reinforcing member which is readily removable from the underside of the housing to

permit the mounting or replacement of lamps in the luminaire, and which will not have any objectionable light leakage around its edges.

A more specific object of this invention is to provide a complete line of recessed luminaires having trough shaped housings which may be fabricated, with the exception of minor alterations dependent upon the particular type of building construction in which such luminaires are employed, from the same forming tools and which utilize the same component parts.

Another more specific object of this invention is to provide a novel reflector structure which may be removed and replaced in luminaires having a trough-shaped housing, from the open side of said housing in order to facilitate repairs to the electrical components of such luminaires without requiring the removal of any other component part.

Another more specific object of this invention is to provide a recessed type luminaire having a trough-shaped housing member having a novel construction whereby the various components comprise an efficient reflecting surface.

These and other objects of this invention will become more apparent when taken in conjunction with the attached drawings, in which:

Figure 1 is a perspective view of a luminaire installation having some parts broken away and shown in section, and other parts shown removed from the position which they normally occupy and illustrating at opposite sides two different type of luminaire support members;

Fig. 2 is a perspective view partially in section and partly broken away of a luminaire installation of a different type than that shown in Fig. 1, for plaster or dry type ceiling or wall constructions, and illustrating one shielding device in an open position;

Fig. 3 is an exploded perspective view of an end of a body member of one type of luminaire and the end plate therefor;

Fig. 4 is a cross-sectional view of one form of a luminaire body member illustrating a center support;

Fig. 5 is an exploded perspective view of an end of a body member of a type of luminaire, different from that shown in Fig. 3, and the end plate therefor;

Fig. 6 is an end view of the type of luminaire shown in Fig. 3 having an end plate positioned thereon with a portion broken away;

Fig. 7 is an exploded partial perspective view, partially in section, illustrating the method of joining two body members of adjacent luminaires; and

Fig. 8 is an exploded perspective view of a hanger bracket and the mounting accessories utilized in supporting luminaires.

In laying out a lighting system utilizing one or more types of recessed luminaires, the method of supporting the luminaires is a matter of choice dependent to a degree of the type of opening and the type of ceiling construction involved. This method of supporting such luminaires in various ceiling constructions has, to a degree, become standardized. One particular generally adopted method of mounting such luminaires is illustrated in Fig. 1 and employs a snap-in locking member which may be of various standard designs. In general, however, all such snap-in locking members are designed so that a standard form of locking flange on the luminaire may be secured thereto. In Fig. 1, two different snap-in locking members are shown, one as standard T-bar 2, the other an inverted heart-shaped snap bar 4. T-bars 2 may be secured in place by suitable means (not shown) and cross-braced, if desired, by any suitable structural members such as channels 6. Snap bar 4, as illustrated, is supported by an adjustable hanger 8 which is suitably

suspended from an upper cross framing or ceiling structure (not shown). A standard flange form may be secured in either T-bar 2 or snap bar 4, ordinarily, however, two T-bars 2 or two snap bars 4 would be utilized rather than one of each, as shown. T-bar 2 and snap bar 4 are each provided with a longitudinal central bottom opening. T-bar 2 has downwardly extending arms 10, each having an outwardly offset bead 12 therein, which are adapted to be engaged by a standard flange shape inserted in the opening 14 between arms 10. Snap bar 4 is provided with downwardly and outwardly sloping side members 15, each of which is terminated in an inwardly rounded reversely bent portion 16. The bent edges 16 are adapted to be engaged both by the hanger 8 and by a standard flange shape inserted in the opening 18 between bent end portions 16.

As shown in Figs. 3 and 7, a luminaire incorporating the features of our invention comprises a trough-shaped body member 20 having downwardly extending side walls 22 each of which has at its lower edge an irregular shaped light trap 21 and an upwardly extending flange 24 having an integral rounded inwardly offset longitudinal bead 26 therein. Bead 26 is one particular standard flange form which is insertable in either opening 14 or opening 18. Thus, opposite sides of the snap-in locking member are of identical form so that the body member may be secured in place merely by pushing upwardly until the engagement of beads 26 with a bead 12 or edge 16 occurs. It will also be noted that by such construction, luminaires of different lengths may be installed end-to-end and that the luminaires may be slidably moved longitudinally in the support members, and that such luminaires are supported on each side for their entire length. Also an acoustic ceiling material 28 may also be snapped into either T-bar 2 or snap bar 4 (depending on which type is employed) not utilized by flanges 24 of the luminaire, in order to provide a ceiling flush with the bottom edge of the luminaire.

Another method of installing luminaires is illustrated in Fig. 2 wherein a non-snap-in type of construction is illustrated. In order to support a ceiling flush against the body member 20, such as a plaster ceiling or dry type ceiling 19, light traps 21 of body member 20 terminate (Fig. 5) in flat flanges 30. The ceiling may be supported by a number of structural cross members, which may be secured in position in any suitable manner. As shown, two different types of support members are arranged in parallel lines. One such support member comprises a U-shaped channel 32 and the other comprises a plaster frame side member 34. If desired, the support members may be cross-braced by channels 36 secured to channels 32 by wire lashing 38. Similar cross bracing may be used with members 34 and suitably secured thereto. A U-shaped hanger 40, channel-shaped in section (Fig. 8), is secured to each support member from which the luminaire is supported, and comprises two downward extending arms 42 which terminate in a central outwardly curved portion 44. Each arm 42 is provided with a series of spaced vertical holes 43 through which, by any suitable means such as a bolt and nut assembly, a variety of tie clips may be secured. The selection of the particular tie clip is dependent upon the particular structural support member employed. When a channel support member such as channel 32 is employed, an L-shaped tie clip 33 is used which is provided on one arm with two holes 50 which may be aligned with holes 43 in either arm 42 of hanger 40 and secured thereto by any suitable means. The other arm of L-shaped tie clip 33 is provided with an elongated slot 52 which allows for attachment to wood furring ceiling members if provided, or for wire lashing clip 33 to channel 32. The selection of the particular mating holes 43 in arms 42 with holes 50 in clip 33 is dependent

upon the size channel 32 or wood member used as a support member.

With support members such as plaster frame side member 34, an irregular-shaped tie clip 56 is used. 5 Curved end portion 44 of arm 42 is positioned against the underside of the cross portion 68 of plaster frame side member 34 at one side of the member 34, and with the other side of cross bar portion 68 of the plaster frame side member 34 engaged by the curved portion 66 of clip 56. As the back portion 58 of clip 56 is provided with holes 60, the hanger 40 is clamped to the plaster frame member 34 by means of bolt assemblies 62 extending through holes 60 and mating holes 43 in an arm 42 of hanger 40.

10 The bight portion 70 of hanger 40 is provided with threaded holes 72 through which machine screws 74 extend, which are utilized with barrel nuts 76 for supporting a luminaire assembly. The bight portion 78 of the body member 20 (Fig. 2) is provided with slots 80, only one of 20 which is shown, so that the body member 20 may be simply placed in position from the underside of hanger 40 so that machine screws 74 extend through slots 80, and then be secured to hanger 40 by means of barrel nuts 76. As machine screws 74 cannot extend through barrel nuts 25 76, body member 20 is secured in place by turning barrel nuts 76 clockwise by means of a screwdriver inserted in their slots 77 so that machine screws 74 may be backed outward from threaded holes 72 in hanger 40, until the flanges 30 of the body member 20 engage the lower surface of the ceiling.

30 It will be noted that each side wall 22 of body member 20 comprises an upper portion 82 which is at approximately a right angle with the bight portion 78 of body member 20, and an outwardly flared portion 84 which is integrally connected either with a flange 24 or a flange 30 by the integral irregular shaped light trap portion 21. Prior to installation of the body member 20, a U-shaped cross member 88, which may be formed from any suitable material such as sheet metal, is mounted in body member 40 20 at each end of body member 20, by any suitable means such as sheet metal screws 89, extending through upper portion 82 of body member 20 and threadedly engaging and extending through the upwardly extending arms 90 at each end of cross member 88. The cross 45 member 88 is positioned at approximately the point where the portion 84 of each side wall 22 starts to flare outward (Figs. 3 and 5).

50 Each U-shaped cross member 88 is provided (Figs. 3 and 5) with integral rectangular offsets 92 at the adjacent end of body member 20, in which downwardly extending lampholders 94 (Figs. 1 and 2) are positioned and which are secured to cross member 88 in any suitable manner. Lampholders 94 are adapted to support fluorescent lamps 95, although the invention is not limited to any specific 55 type of light source. Body member 20 can be of various lengths and the position of cross members 88 and lampholders 94 may be varied in order that various lengths of lamps 95 may be utilized.

60 A ballast unit 96 (Fig. 1) is installed, by any suitable means, such as a plurality of bolt and nut assemblies 98, upon the bight portion 78 of the body member 20. Once ballast 96 is installed, the requisite wiring of the luminaire may be accomplished and located in the chamber formed by the cross members 88 and the upper part of body member 20. A number of standard knockouts (not shown) should be provided both in the upper portions 32 of side walls 22, and in the bight portion 78 of body member 20, as may be needed. A reflector plate 100 is 65 secured to the cross members 88 by suitable means, such as by the downwardly extending machine screws 102 which are threadedly engaged in cross members 88. Reflector plate 100 is provided with slots 104 at each of its ends which are slightly greater in width than the diameter of machine screws 102 so that either slot 104 of reflector 70 75

plate 100 may be initially slid into place to receive the machine screw 102 at one end and a nut 105 placed thereon to hold one end of reflector plate 100 loosely in position. By positioning reflector plate 100 so that this screw 102 engages the bottom of one slot 104, the other end of reflector 100 will clear a previously positioned screw 102 and nut 105 extending downward from the cross member 88 at the other end of body member 20. By then moving reflector plate 100 toward the other screw 102, both screws 102 can be located at an intermediate position of the respective slots 104 and the reflector plate 100 secured to each cross member 88 by the nuts 105. It will be noted that exactly the reverse process can be followed in removing reflector plate 100, so that the ballast 96 and the wiring will be accessible from the underside of body member 20, all without removing the nuts 105.

The irregular-shaped light trap 21, which joins either flange 24 or 30 with the lower portion 84 of each side wall 22 of body member 20, comprises an upwardly extending portion 106 from flange 24 or 30, a short cross portion 108 at approximately right angles to upwardly extending portion 106, and a downwardly sloping portion 107 joining cross portion 108 with lower portion 84 in a plane below the plane of cross portion 108. Each upwardly extending portion 106 is provided with spaced T-shaped slots 109 (Fig. 1) having stem portions in alignment with rectangular slots 111 in either flanges 24 or 30. Slots 109 and 111 are provided so that a door assembly 110 or louver assembly 135 may be installed as a shielding device to control light passing through the open bottom of the luminaire. As shown in Figs. 1 and 6, door assembly 110 comprises a rectangular frame having side members 112 and end members 123 which may be removably secured together in any suitable manner (not shown). Both side members 112 and end members 123 are provided with integral upwardly extending flanges 117 at the outer edge thereof for the purpose of providing a continuous light trap cooperable with light trap 21 of the body member 20. Side members 112 are also provided with an integral channel 113 to support a glass or other translucent panel member 115 at its sides along its entire length.

As shown in Fig. 2, louver assembly 135 may comprise a frame having channel side members 114 and channel end members 125 which may be secured together in any suitable manner, such as by welding or brazing. Both side members 114 and end members 125 are provided with an integral upwardly extending flange 141 at their outer edges similar to flange 117 of door assembly 110 whereby a continuous light trap is formed which is cooperable with light trap 21 of body member 20. Louver assembly 135 comprises a plurality of spaced cross members 116 which are secured at their ends to side members 114, in any suitable manner, such as welding or brazing.

Door assembly 110 and louver assembly 135 are each provided with a pair of laterally extending stationary T-shaped hinges 118 which may be inserted into the slots 109 of light trap 21 at either side of the body member 20, whereby either door assembly 110 or louver assembly 135 may be removably pivotally mounted to the flanges 24 or 30 by the stem portion of T-shaped hinges 118 extending through the narrow portion of the T slots 109 when closed, and through slots 111 when open. The side frame members 112 and 114 are also provided with a pair of spaced T-shaped latches 120 on the side of the door assembly opposite from T-shaped hinges 118. The latches 120 are adapted to engage the adjacent slots 109 when extended to latch door assembly 110 across the opening of body member 20. The method of supporting and latching door assembly 110 and louver assembly 135 forms no part of this invention and is fully described and claimed in the copending application of Nick Stuffer and Leonard H. Seeley on Luminaires, Serial No. 348,666, filed concurrently with this case and assigned

to the same assignee as this invention. For a more complete description of this feature, the above-identified application is referred to.

In order to close the open ends of the body members 5 20, each flared portion 84 of side walls 22 is provided at its outer edges with a rectangular notch 300 and with a slot 122 displaced inwardly from and approximately parallel to notch 300. A hole 124 is provided between notch 300 and slot 122, and a slot 126 is provided in the bight portion 78 of body member 20. As shown in Figs. 3 and 5, end cover 128 is provided with an upwardly extending tab 130, and a tab 132 at each of its sides having a laterally inwardly extending flat portion 134 with a hole 136 therein. Side tabs 132 are also provided with angular outwardly extending triangular projections 138. End cover 128 may simply be placed in position by moving the end plate 128 upwardly so that extending tab 130 is received in slot 126 and at the same time projections 138 enter slots 122, until flat portions 134 rest flush 10 against the inner side of outwardly flared portions 84 of side walls 22. Holes 124 and 136 are then aligned and end cover 128 may be secured in place by any suitable means such as sheet metal screws, not shown, inserted through these aligned openings. Fig. 6 illustrates 15 in part such an end cover secured in place. If desired, a U-shaped sheet metal nut 196 (Fig. 7) having an inner clearance opening 302 in one of its legs in alignment with an opening 198 having inwardly facing projections 301 in the other of its legs, may be inserted over lower portion 84 of each side wall 22 so that its bight portion engages the bottom of notch 300 and so that hole 124, opening 198 and opening 302 are in alignment. As sheet metal nuts 196 are usually fabricated from a light gauge of sheet metal and are formed with their arms bent 20 towards each other, a spring force is produced between the arms which holds the nuts 196 on the side walls 22. With such an assembly, the inner leg of a nut 196 is positioned between the flared portion 84 of a side wall 22 and flat portion 134 of an inserted end cover 128. A 25 sheet metal screw having a cone shaped end, such as screw 194 (Fig. 7), may then be manually inserted into sheet metal nut 196 and engage projections 301 and be supported thereby until the end cover 128 is tightly secured (at each of its sides) to body member 20 by tightening 30 screws 194. If desired, end cover 128 may be provided with a standard knockout 127 in order to facilitate the wiring of the luminaire. With the type of ceiling installation shown in Fig. 2, where an outwardly extending flange 30 is required, an end flange member 142 having 35 an upright portion 144 with inwardly extending tabs 146 may be secured to end cover 128 by inserting tabs 146 in slots 140 in end cover 128 and bending tabs 146 backward against the inner surface of end cover 128.

Body member 20 may be of varying lengths, however, 40 in order to accommodate the present day standard 8 foot lamp, additional problems are encountered. One difficulty encountered is in providing a door assembly 110 and louver assembly 135. In general, a single door of such length has not proven practical, therefore two shielding devices in a tandem arrangement has been adopted. Such an arrangement entails a problem of objectional light leakage between the shielding devices and the luminaire, both along the sides and ends. Another difficulty encountered in long luminaires is that they have a 45 tendency to bow and sag and therefore do not hold their shape over their entire length. Also, the reflector members 100 tend to sag downward objectionably. In keeping with the objects of our invention, we have provided 50 a novel center support which overcomes the difficulties of long length luminaires.

Our novel center support means (Fig. 4) comprises an inverted U-shaped cross brace 150, which may be fabricated from any suitable material such as sheet metal, and has its legs secured to upper portions 82 of each side wall 55 22 of body member 20 by any suitable means, such as

thread cutting screws 152. A reflector plate 154 which is identical with the reflector plate 100, previously discussed, except that a central V ridge 155 is provided to increase its rigidity, is positioned against the underside of cross brace 150 and secured thereto by a machine screw 156 extending through holes in cross brace 150 and V ridge 155, and which is threadedly engaged by a nut 158 bearing against the apex of the V ridge 155. If desired cross member 88 may also be provided with a V ridge (not shown) to provide additional bracing for reflector plate 154.

The lower portion 84 of each side wall 22 of body member 20 is cross supported by means of an approximately channel-shaped brace 160 having upwardly extending U-shaped tabs 162 at each end which are insertable in slots, not shown, in light traps 21 of body member 20. Tabs 162 are provided with extending ends 164 to position cross brace 160 with reference to body member 20 by engaging cross portion 108 of light trap 21 of body member 20. The slots in light traps 21 of body member 20 are such that the arms of U-shaped tabs 162 are freely insertable into said slots, and the brace 160 is biased to such position by a spring 168. Brace 160 is slidably and pivotally mounted at its mid-point in order that it may be removed from the slots in the light trap 21 and swung to a position approximately parallel with the lamps. This is accomplished by providing a U-shaped bracket 172, which may be formed of any suitable material such as sheet metal, and is removably secured to reflector 154 by means of machine screws and nut assemblies 174 extending through integral tabs 176 of bracket 172, through reflector plate 154 and through slots (not shown) in brace 150 which extend to one side edge of brace 150. The lower cross portion 178 of bracket 172 is provided with a hole through which a stud 166 extends which is secured to cross brace 160 by any suitable means such as welding or brazing. A coil compression spring 168 is provided upon stud 166 and it engages the upper surface 167 of the cross portion 178 of bracket 172 and is held compressed by any suitable means, such as the nut 170 threadedly engaging stud 166. If desired nut 170 may be secured to stud 166 in any suitable manner, such as by staking, so that it cannot be removed by hand.

In operation, cross brace 160 is pulled downward thereby compressing spring 168 so that a sufficient clearance is provided to permit removal of tabs 162 of cross brace 160 from slots in light traps 21 of body member 20. Thereafter brace 160 may be freely rotated and then released and held in any desired released position by means of the spring 168. After such a luminaire has once been relamped, the reverse process is followed. It will also be noted that as screw and nut assemblies 174 are positioned within slots in brace 150, cross brace 160 may be completely removed along with the reflector 154 by merely loosening assemblies 174 and moving reflector 154 endwise until assemblies 174 clear the slots in brace 150.

As shown in Fig. 2, applicants have provided an upper tie plate 180 which may be removably secured to each bight portion 78 of body member 20 of each of two adjacent luminaires by means of a plurality of bolt and nut assemblies 182. The lower portion of each luminaire is fixedly positioned with reference to each other by means of a novel connector 184 (Fig. 7) which is provided with means to engage slots 122 in the lower portions 84 of each side wall 22 of the two adjoining body members 20 at each side of connector 184. Connector 184 comprises an inverted U-shaped cross bar portion 186 having at each of its ends an integral angular upwardly extending portion 188 each of which is provided at each of its sides with a triangular projection 192 which are at exact right angles to portion 188. When the connector 184 is placed in position from the underside of body member 20, the angular portions 188 then rest flush against the

inner legs of the nuts 196 which have previously been positioned in notch 300 of body member 20 so that their openings are in alignment with hole 124 of lower portions 84, and so that triangular projections 192 enter slots 122. Each angular portion 188 is also provided with two slots 190 so that when connector 184 is inserted from the bottom of the body members 20 and tabs 192 engage slots 122 in the lower portions 84 of side walls 22 of body members 20, slots 190 are in alignment with holes 124 in lower portions 84 of each side wall 22 of each body member 20. Connector 184 may then be removably secured to each body member 20 by any suitable means such as pointed sheet metal screws 194 extending through slots 190 through the openings 124 in side walls 22 of each body member 20, and engaging U-shaped speed nuts 196. It will also be noted that the engagement of triangular projections 192 of connector 184 with slots 122 of each side of adjacent body members 20 forces lower portions 84 of adjacent body members in their correct position.

Luminaires constructed in accordance with our invention eliminate objectionable light leakage between the shielding devices 110 and 135 and the body member 20, and, depending upon the particular construction, end covers 128, connectors 184 or cross braces 160. Since the flanges 117 of door frame 112 are located outwardly of the lower edges of portions 84 of the housing side walls and beneath light trap portions 108, no direct light is directly observable from below. Any light striking the horizontal portion of the side member of the frame 112 will be reflected upward toward flange 117 which in turn will reflect the light inwardly back into the body member 20. Similarly any direct light rays striking flange 117 will be reflected back into the body member 20. The direct light rays from lamps 95, as well as the reflected light rays from lower portions 84 of side walls 22, cross member 88, reflector plates 100 or 154, which are all reflecting surfaces, which enter the space 123 are first reflected from the inner surface of frame 112. If desired, the inner surface of frame 112 may be finished with a light absorbing black paint in order that most of the incident light would be absorbed. The remainder of the light rays which are reflected through light trap 21 of body member 20 are dissipated by multiple reflections between flange 117 of door assembly 110 and the upright portion 106 of the light trap 21. Thus, any light passing through the opening between channels 113 and portions 84 will be so reflected by flange 117 that no direct light leakage will occur to the exterior. The construction of flange 141 of louver assembly 135 is substantially identical with flange 117 of door assembly 110 so that objectionable light leakage will be prevented with the louvered type construction. End covers 128 (Figs. 3 to 5) are provided with inward light trap offsets 129 at their lower edges in which either flange 117 or 141, dependent upon whether door assembly 110 or louver assembly 135 is installed, may be positioned in overlapping relationship with offset 129 so that no objectionable light leakage will occur between door assembly 110 or louver assembly 135 and end members 128, in the same manner as previously discussed. In a similar manner cross brace 160 and connector 184 are provided with downwardly extending arms 131 and 133, respectively, between which flanges 117 or 141 of two adjacent door assemblies 110 or louver assemblies 135 may be positioned. It is thus apparent that light trapping provisions are made for all four sides of the two types of doors illustrated, whether only a single door is employed, or a plurality of doors are arranged end to end.

Thus, it will be observed that we have a novel basic luminaire which is readily adapted to be utilized in a variety of different lighting installations. Primarily, as the body members utilized with different methods of support are identical with the exception of the outermost flanges, the same basic methods of fabricating and the

same component parts may be used. It is obvious that such an arrangement results in substantially lower production costs. Further, it will be noted that our luminaires are readily adapted to be installed and easily serviced from the underside of the luminaire without tools or loose parts resulting in substantial installation savings over the method of installing presently employed. It will also be more particularly noted that the lower portions of the body members, the reflector and the cross plates all function as light reflecting surfaces. During installation, both the connectors and the end plates hold the contour of the body member thereby insuring that all the body members are in alignment. In servicing, the fact that all parts of the luminaire including the wiring and the ballast unit thereof are accessible from the underside results in a substantial reduction in servicing cost. It will also be noted that although our luminaires result in substantial savings to the purchaser that such savings are accompanied by a superior luminaire. Thus, the interchangeability of parts which permits a luminaire to be used alone, in pairs, or in a line or lines, results in a lighting system which may readily be altered if desired, due to future lighting requirements.

Although we have shown and described one particular line of luminaires which incorporate the various features of our invention, in accordance with the patent statutes, we are aware that other modifications may easily be made without departing from the spirit of our invention.

We claim as our invention:

1. A luminaire including an open ended trough shaped body member having downwardly extending side walls, means secured to said body member for supporting lamp holding means between said side walls, a lower cross brace rotatably located below said lamp holding means and mounted for movement on said body member between said side walls, said brace having extending arms at each of its ends engageable with apertures in each of said side walls upon upward movement of said brace, spring means for biasing said brace upwardly, said spring means being compressible to permit said brace to be withdrawn from engagement with said apertures and rotated between said side walls.

2. A luminaire comprising an open ended trough shaped body member having downwardly and outwardly extending side walls, means for supporting lamp holding means between said side walls, at least one covering means spanning one end of said body member to close said one end of said body member, said covering means being located between said side walls at said one end and having integral tabs at each of its sides which extend inwardly along and in engagement with the inner surface of said side walls, each of said tabs having an integral angularly outwardly extending projection thereon at its free end, each of said side walls having an aperture therein at each of its ends through which one of said projections extend, and means for securing said tabs to said side walls.

3. A lighting system comprising, two inverted trough shaped luminaires mounted end-to-end, a connector adapted to be inserted from the underside of said luminaires at the juncture of said luminaires between the side walls thereof to a position where it spans said side walls adjacent the free ends thereof at said juncture, an integral plate at each end of said connector extending angularly upwardly relative to said connector so that said plates are positioned against the lower portions of the inner sides of said walls of the luminaire, respectively, and spanning said juncture, tabs extending outward from each plate of said connector engaging apertures in adjacent side walls of said luminaires, respectively, means for securing said extending plates to the adjacent side walls of said luminaires.

4. A lighting arrangement including at least two abutting luminaires each comprising an inverted open ended trough shaped body member, means secured to

said body members for supporting lamp holding means between the side walls thereof, each of said side walls having an aperture adjacent its abutting end and at the lower edge thereof, a connector spanning said side walls at their abutting ends and located below said lamp holding means and comprising an inverted channel shaped member, a plate secured at each end of said channel in an angular relationship therewith, each of said plates spanning the abutting ends of said side walls and having integral projecting means engaging said apertures in the adjacent side walls of said body members to hold said body members in abutting relationship, and means for removably securing said plates to said side walls.

5. A luminaire comprising an inverted trough shaped body member, means secured to said body member for supporting lamp holding means between the side walls thereof, each of said side walls being provided at each of its ends near its lower edge with a slot in juxtaposition with a first opening but spaced therefrom the same predetermined distance as the other juxtaposed openings and slots, a cover on one end of said body member having inwardly extending tabs at each of its sides engaging the inner surfaces of said side walls and having a second opening therein, said tabs having integral outwardly extending ends received within opposed ones of said slots and spaced from said second openings in the aforesaid predetermined distance whereby said first and second openings are aligned, means cooperable with said first and second openings for securing said cover to each of said side walls, a connector spanning the lower ends of said side walls at the other end of said luminaire and having an upwardly extending portion at each of its ends at least part of which engages the inner surface of said side walls to connect the other end of said body member with another similar body member, each of said extending portions having spaced outwardly extending portions one of which is secured in the adjacent slot and the other of which is located outwardly of said other end of the luminaire.

6. A lighting system comprising two inverted trough shaped luminaires supported in tandem so that adjacent ends abut each other, the side walls of said luminaires diverging, an opening in each side wall of each luminaire adjacent both its abutting end and its free side edges, an elongated connector spanning the free ends of the side walls of said luminaires at their abutting ends and having an integral plate at each of its ends which extend generally upwardly and spans the abutting adjacent side walls of said luminaire, spaced tabs on each of said plates extending outwardly therefrom, and said tabs being received in said openings in adjacent side walls so that said connector may be inserted from the open side of said housing with said plates engaging the inner surface of said side walls, and means for removably securing said plates to said side walls.

7. A luminaire including an open ended inverted trough shaped body member, means secured to said body member for supporting lamp holding means between the side walls thereof, a lower inverted channel shaped cross brace located below said lamp holding means and mounted at an intermediate point on said body member between said side walls for substantially vertical sliding movement toward and away from the right portion of said body member and for pivotal movement from a position where it extends transversely of and spans the sides of said body member to a position substantially parallel to said sides of the body member, said brace having upwardly extending arms at each of its ends automatically engageable in apertures in divergent portions of each of said side walls upon upward movement of said brace to locate said brace in operative position at the free edges of said side walls of the body member, and spring means for biasing said brace upwardly to its operative position.

8. A luminaire including an open ended inverted

trough shaped body member, means secured to said body member for supporting lamp holding means between the side walls thereof, a lower cross brace located below said lamp holding means and mounted at an intermediate point on said body member between said side walls for substantially vertical sliding movement toward and away from the bight portion of said body member and for pivotal movement from a position where it extends transversely of and spans the sides of said body member to a position substantially parallel to said sides of the body member, said brace having upwardly extending arms at each of its ends automatically engageable in apertures in divergent portions of each of said side walls upon upward movement of said brace, and spring means for biasing said brace upwardly to its operative position.
